UNITED STATES PATENT OFFICE.

BON E. MYERS, OF SIOUX CITY, IOWA.

STORE-FRONT CONSTRUCTION.

Application filed July 19, 1926. Serial No. 123,266.

My invention relates to the sash construction for holding the glass in place in a store front construction and it is my object to provide simple, durable and inexpensive means for securing the glass, including a pair of sash members to engage either side of the glass and a tie link for connecting the two sash members, said link being operable from the outer side of the store front during installation by means of a screw driver or the like.

More particularly it is my object to provide a construction including such a tie link, the length being so constructed and arranged relative to the sash member that it will be stopped or locked against further rotation at a certain point in the process of connecting the sash members by means of a link, whereby undue pressure can not be imposed upon the glass between the sash members by virtue of the driving of said link into connecting engagement with the two sash members.

More particularly referring to the last object it is my purpose to provide a tie link having a threaded engagement with both of the sash members which it connects and a position adapted to engage one of the sash members to limit the rotation of the link relative to that member and to lock the link by wedging of its threads against retrograde movement.

A still further object is to provide an arrangement in which the link will positively move the sash members toward each other at a pre-determined rate as the link is driven into its connecting engagement with the sash members, the parts being so arranged that when the link has been driven to its limit and there stopped by engagement of its engaging portion with one of the sash members, the sash members will have approached to within a pre-determined distance from each other in order to impose upon the glass a pre-determined strain, whereby the amount of strain imposed upon the glass between the sash members at each point of connection will be uniform.

With these and other objects in view, my invention consists in the construction, arrangement and combination of the various parts of my device, whereby the objects con-

templated are attained, as hereinafter more fully set forth, pointed out in my claims, and illustrated in the accompanying drawings, in which:

Fig. 1 has a sectional perspective view of a store front construction embodying one form of my invention.

Fig. 2 is a transverse sectional view of the same.

Fig. 3 is a rear elevation of the outer sash member shown in Fig. 2.

Fig. 4 is a transverse sectional view similar to Fig. 2, of a somewhat modified form of my invention.

Fig. 5 is a similar sectional view of a further modified form of my invention.

Fig. 6 is a sectional perspective view taken from the rear of the outer sash member shown in Fig. 5.

Fig. 7 is a horizontal sectional view through a dividing post embodying one form of my invention.

Fig. 8 is a sectional view similar to Fig. 2, showing a form of my invention in which the tie link serves to positively move the connecting sash toward each other to exert a pre-determined pressure upon the glass.

Fig. 9 is a longitudinal, enlarged sectional view through the tie link of Fig. 8.

Fig. 10 is a sectional view similar to Fig. 2, illustrating a somewhat modified form of the device illustrated in Fig. 8.

Fig. 11 is a view similar to Fig. 9 of the tie link shown in Fig. 10 and Fig. 12 is a horizontal, sectional view illustrating a corner post embodying my invention as shown in Fig. 10.

It is common knowledge in the store front construction art that it is desirable to connect the sash members which hold a pane of plate glass with a small amount of pressure sufficient to hold the glass firmly in place and yet not enough to place the area of glass surrounding the tie link under a strain which will make the glass susceptible to splitting or cracking in the zone of strain when it is subjected to vibration or pressure from external sources.

Many methods have been devised of connecting the sash members so that the pressure exerted upon the glass may be neglected but most of such devices are somewhat

complicated and involve considerable difficulty in installation.

My invention involves the use of a tie link which, in its most simple form, has a common wood screw and which may be inserted and driven to connecting position from the outer side of the store front. In Figs. 1, 2, 4, 5, 8, and 10 I have shown the ordinary horizontal portion over a window frame in which 10 indicates the window ledge and 11, a wooden shoulder against which the glass or an intermediate sash member is adapted to be engaged.

The glass 12 is ordinarily rested upon wooden blocks 13 and in the forms shown in Figs. 2 and 5 the shoulder 11 forms one of the inter sash members for holding the glass.

In the forms shown in Figs. 4, 8, and 10, an intersash member of sheet metal is provided, having the vertical wall, 14, secured to the shoulder, 11, by means of wood screws, 15, a horizontal frame, 16, projecting forwardly and a forwardly bent portion, 17, terminating in a vertical flange to receive the glass.

The outer sash member comprises generally a molding having the ornamental wall portion 19 including a vertical portion, 20, to receive the tie link, a lower horizontal flange 21 to rest against the ledge 10 or the flange 16 as the case may be, and the intervertical flange 22 to engage the outer face of the glass.

In Fig. 7 I have illustrated a horizontal dividing post, having an outer sash member comprising a channel shaped portion 23 and co-planar flanges 24 to engage the adjacent plates of glass on one side.

The inner sash member comprises a plate 25 having inturned flanges 26 to engage the other sides of the respective glass plates. At spaced intervals along the inner sash member, brackets 27, having arms 28 secured between the flanges 26 and plate 25 are provided in order to receive the threaded ends 45 of the tie links. For this purpose the tie links are provided with threaded openings at 29.

In the forms of my invention shown in Figs. 2, 4, 5, and 7, I provide an arrangement in which the pressure to be had between the sash members is determined by manual pressure from the operator and in which the tie link does not, in itself, operate to impose pressure upon the glass but only preserves the hand of the operator. I accomplish this in a very simple manner, the tie link being operable from the outer side of the sash by one hand of the workman and the pressure exerted by the other one.

An ordinary wood screw 30 may be employed for this purpose and in the forms shown in Figs. 2, 4 and 5 it is extended through the vertical portion 20 of the outer sash member and into the other shoulder 11.

A small hole is drilled in the shoulder 11

in order to facilitate entrance of the screws and in order that the screw, at its inception, may not exert a back pressure against the manual pressure designed to give the sash members a grip upon the glass.

The screw 30 has the ordinary slotted head 31 which, when the screw has been driven to the proper depth, will engage the vertical wall 20 of the outer sash member.

In order that such engagement of the head with the sash member may not add to the pressure imposed upon the glass, I provide for stopping the rotation screw immediately when the head has so engaged the wall 20. To this end I provide in Figs. 2 and 4 an L shaped bar 32 arranged opposite each of the screw openings in the wall 20 and retained by the flanges 16 and 22 in the manner shown.

The two legs of the bars 32 are sprung into place behind the flanges in such a way that the ends of the legs will engage the walls 22 and 22^a respectively and a bar thus firmly held in place. A threaded opening, 33, is provided in the bar 32 and aligned with the respective screw opening.

Since screw 30 is threaded into the opening, 33, it will be seen that this thread engagement will serve to advance the screw relative to the sash member 19 rather than the thread engagement with the shoulder 11. This advancement will be stopped by the engagement of the head 31 with the wall 20 and consequently the rotation of the screw will be also stopped and the screw may be wedged tightly against retrograde rotation by pressure upon the screw driver.

The bar 32 being of very substantial construction the strain thus set up between the bar and the wall will not bend it. This strain is transmitted directly by the horizontal leg bar to the wall 20.

By stopping the rotation of the screw immediately when the head 31 has engaged the sash member it will be seen that this engagement will not serve to draw the sash member toward the shoulder 11.

Were there no check upon the rotation of the screw, it will be seen that further rotation after the head 31 has engaged the sash member would drive the screw deeper into the shoulder 11 and draw the sash members toward each other.

In Fig. 5 the function of the bar 32 is served by a sleeve 34 having a threaded portion 35 and secured to the flange 21 by means of integrally formed ears 36, as shown in Fig. 6.

In Fig. 7 the bar 32 is replaced by a yoke 37 similar to the bracket 27. The yoke 37 has a threaded opening 38 to receive the screw.

In Figs. 8 to 12 inclusive, I have shown a similar construction to that previously described in which the tie link or screw mem-

ber has the added function of automatically determining the amount of pressure to be placed upon the glass.

In these forms of the invention the function of the bar 32 is served by a fairly deep boss or collar 39 which may be drawn integrally with the sash member 19 or formed as a separate boss swaged into the wall 20.

The tie link is in the form of a machine screw having a threaded portion 40 adapted to be threaded into the collar 39 and a head 41 adapted to engage the wall 20 surrounding the collar 39. Rotation of the screw will be stopped when the head 41 has thus engaged the wall 20 in the same manner as previously described.

In the forms shown in Figs. 8 and 9 the screw is provided with a reduced portion 42 adapted to clear the threads of the collar 39 and having a portion somewhat greater than that of the threads 40.

A boss 43, swaged into the portion 14^a of the rear wall 14, has a threaded bore 44 to receive the threaded portion 42 of the screw.

In assembling the store front the two casing members are placed in a parallel position with the glass between them and with the screw members of the tie links entirely removed. The screws are then inserted in such a way that the threads 42 and 40 will enter their respective thread openings at the same time.

It will now be seen that when the screw has been driven home the same number of threads of the screw portion 42 and 40 respectively will have entered the boss 43 and collar 39 respectively and that during this entrance the collar 39 will have been moved toward the boss 43 a distance corresponding to the difference in pitch of the respective threads multiplied by the number of threads which have entered. This difference in pitch is made very slight and the length of the screw is regulated so that when the screw is ready to enter both boss 43 and collar 39 simultaneously the member 19 will be in very close proximity to the glass whereby a very slight amount of adjustment of the member 19 will cause it to grip the glass.

By making the necessary movement between the members small it will be seen that any inaccuracy of adjustment which may be encountered by reason of one of the threads 42 or 40 being started in its respective opening ahead of the other, will be correspondingly reduced.

In the forms shown in Figs. 10, 11, and 12 the screw member of the tie link has one of its threads 40^a formed on its exterior and its other thread 42^a formed as an interior thread.

Instead of the boss 43 a common bolt 43^b may thus be used and secured in the wall 14^a by means of a locknut 43^b.

In all of the forms shown in Figs. 8 to 12

the head 41 stops the rotation of the screw in the same manner as in the forms shown in Figs. 1 to 7 inclusive, locks the screw against retrograde movement and in connection with the screw 40 or 40^a prevents the screw being rotated beyond the point where the sash members are properly spaced in and under the proper pressure.

In Fig. 12 I have shown a corner post having the outer sash member 25^a, the bracket 27^a secured by the flanges 26^a and inner sash member 23^a having the glass engaging flanges 24^a.

The tie link construction shown in Fig. 11 is illustrated in connection with the corner post construction although the tie link shown in Fig. 9 could equally as well be used.

Either of the tie links shown in Figs. 9 or 11 may be used with the dividing bar shown in Fig. 7.

In some instances the head of the screw member of the tie link may interfere with the assembling of a window construction and dispose to dispense with the head when desirable. It will be seen that by adjusting the length of the screw to the sash members so that the other end, thereof, will be flush with some portion of the sash member 19 such as the outer surface of the wall 20, at the point where the proper pressure between the sash members has been attained, it will be possible to form the screw driver slot in the screw portion itself and to stop rotating the screw when the end has arrived at a position flush with the proper indicating surface. The stopping will not be automatic with such a construction and will depend upon the eye of the operator but a skillful workman will be able to attain practically the same result as where the stopping is done automatically by the contact of the head of the screw with the sash member.

I claim as my invention:

1. In a store front construction, a pair of sash members to engage the respective sides of a pane of glass, one of said members having a threaded opening, and a tie link having a threaded connection with the other sash member and a threaded portion threaded through said opening so that rotation of the link will simultaneously advance it in the same direction relative to both members, said link having a portion adapted by contact with the member having the threaded opening, to limit the rotation of the link in said opening.

2. In a store front construction, a pair of sash members to engage the respective sides of a pane of glass, a tie link having a threaded connection with each member, such that rotation of the link will simultaneously advance it in the same direction relative to both members, said link having a portion adapted by contact with one of the members to limit

the rotation of the link relative to said last mentioned member.

3. In a store front construction, a pair of sash members to engage the respective sides of a pane of glass, a tie link having a threaded connection with each member, such that rotation of the link will simultaneously advance it in the same direction relative to both members, but at different rates of advance, to draw the members toward each other at a predetermined rate as said link is advanced, said link having a portion adapted by contact with one of the members to limit the rotation of the link relative to said last mentioned member, when the members have approached to within a predetermined distance from each other.
4. In a store front construction, a pair of sash members to engage the respective sides of a pane of glass, a tie link having a threaded connection with each member, such that rotation of the link will simultaneously advance it in the same direction relative to both members, but at different rates of advance, to draw the members toward each other at a predetermined rate as said link is advanced.

5. In a store front construction, a pair of sash members to engage the respective sides of a pane of glass, one of said members having a threaded opening, and a tie link having a threaded connection, of different pitch from that of the threaded opening, with the other sash member and a threaded portion threaded through said opening, so that rotation of the link will simultaneously advance it relative to both members but at different rates so as to draw the members toward each other at a predetermined rate as said link is advanced, said link having a portion adapted by engagement with the member having the threaded opening to limit the rotation of the link when the members having approached to a predetermined distance from each other.

6. In a store front construction, a pair of sash members to engage the respective sides of a pane of glass, one of said members having a threaded opening, and a tie link hav-

ing a threaded connection with the other sash member and a threaded portion threaded through said opening so that rotation of the link will simultaneously advance it in the same direction relative to both members, said link having a head adapted by contact with the member having the threaded opening, to limit the rotation of the link in said opening, said head being formed to receive a tool for driving the link.

7. In a store front construction, a pair of sash members to engage the respective sides of a pane of glass, a tie link having a threaded connection with each member such that rotation of the link will simultaneously advance it in the same direction relative to both members, said tie link extending through one of the members.

8. In a store front construction, a pair of sash members to engage the respective sides of a pane of glass, a tie link having two threaded portions of varying pitch and diameter, one of said portions having a threaded connection with one sash member and the other threaded portion having a threaded connection with the other sash member whereby rotation of the link will simultaneously advance it in the same direction relative to both members.

9. In a store front construction, a pair of sash members to engage the respective sides of a pane of glass, a tie link having a first threaded portion threaded through one of said sash members, said tie link having a head adapted to engage the last mentioned sash member to limit the rotation of the link, said tie link having a second threaded portion of smaller diameter and of different pitch than the first threaded portion, said second threaded portion having a threaded connection with the other sash member whereby rotation of the link will draw the sash members together at a predetermined rate of advance.

Signed this 15th day of July, 1926, at Sioux City, in Woodbury County, State of Iowa.

BON E. MYERS.
